PILE WIRE INSERTING MEANS FOR LOOMS

Raymond Sutcliffe, Cornwall, N. Y., assignor to
Firth Carpet Company, Firthcliffe, N. Y., a corporation of New York

Application March 1, 1934, Serial No. 713,466

5 Claims. (Cl. 139—42)

This invention relates to pile wire inserting means for looms and has for its object to provide a simple and efficient apparatus by which the pile wires, over which the warp pile loops are formed, can be inserted with accuracy and extreme rapidity.

Heretofore, in looms of this character, the pile wires have been inserted and withdrawn by means of a complex and intricate mechanism which not only added greatly to the manufacturing cost of the loom but did not operate with a maximum of efficiency as far as inserting the wires in the shed with the greatest possible speed was concerned. My invention therefore, contemplates a relatively simple mechanism which will insert the pile wires in the shed with accuracy and speed and which, through an arrangement of relatively few parts will materially increase the speed of wire insertion.

In the accompanying drawings, wherein an embodiment of the invention is shown, Fig. 1 is a plan view of the pile wire inserting mechanism; Fig. 2 is a sectional view on the line 2—2 of Fig. 4, looking in the direction of the arrows; Fig. 3 is a sectional view on the line 3—3 of Fig. 4, looking in the direction of the arrows; Fig. 4 is a plan view of a portion of the wire-inserting mechanism; Fig. 5 is a side elevation of the mechanism shown in Fig. 4, with some of the parts in section; Fig. 6 is a sectional view on the line 6—6 of Fig. 4, looking in the direction of the arrows; and Fig. 7 is a diagrammatic view showing the course of the chain which returns the wire-inserting carriage.

In the drawings, 10 indicates the woven fabric, which may be carpeting or other fabric in which a warp pile is produced. The shed is indicated at 14 and the warp pile picks at 12. At 13 is shown a number of pile wires which have been successively inserted in the shed. One of the pile wires 13 is shown in detail in Fig. 2, where it will be seen that the same consists of an elongated flat strip, nearly rectangular in cross section. On its upper edge adjacent its pointed end it is formed with a sharpened blade 11 which on the longitudinal withdrawal of the wire from under the pile loops, acts to sever these loops. The structure thus far described is common in loom construction.

At 15 is shown a carriage which, on its return movement to the right of Fig. 1, engages the inserted wire 13a and withdraws it out of the fabric, and then on its movement to the left in that figure, under the propulsion of a spring-pressed plunger inserts the wire in the shed. The car-

riage has a flat or horizontal plate portion 16 provided with a vertical flange 17. Secured to the outer face of the vertical flange 17 by screws 18 is a plate 19 (Fig. 5) having a laterally extending top flange 22 and a downwardly extending lug portion 20 carrying a projecting stud 21.

The carriage is moved to and from the fabric with a reciprocating movement on a frame member 30 which is provided with a longitudinal guide groove 31 in which complementary shaped blocks 32, secured to the under side of the plate 16 of the carriage, are guided (see Fig. 3). These guide blocks 32 are attached to the plate 16 by means of the bolts 36 which also secure a plate 37 to the upper face of the plate 16. Plate 37 is provided with a vertical flange 38. Pivoted at 24 in the bosses 25 and 26, provided on the flanges 17 and 38 respectively, is a pawl 23 which is normally dependent through an opening 39 in the plate 16 so that its lower hooked end 40 (Fig. 6) is located in position to form an abutment for the hook-shaped member 41 carried by a chain 42. The chain 42 has its upper stretch movable through the lower portion of the guide groove 31 so that at the proper time the hook 41 will engage the end 40 of the pawl 23 and by pressure thereagainst will force the carriage to the right of Figs. 1 and 4 to cause it to withdraw one of the wires from the fabric, and particularly the then innermost wire, indicated at 13a.

The pawl 23 is normally held in its operative position, as shown in Fig. 6, to act as an abutment for the hook 41 by means of a dog 43 which is pivoted at 44 in the bosses 45 and 46 (Fig. 4) formed on the flanges 17 and 38 respectively. The lower end of the dog 43 is held in engagement with a notch 47 formed in the pawl 23, by means of a spring 48 having one of its ends attached to a pin 49 projecting from the side of the dog and its other end attached to a pin 50 projecting from the plate 37.

At 51 is shown a cylinder provided with a pair of downwardly extending lugs 52 which are secured by means of the screws 53, to the frame member 30. The cylinder 51 acts as a housing for a helical spring 54 which surrounds a plunger rod 55 that has an end 64 projecting out of one end of the cylinder 51 as clearly shown in Figs. 4 and 5. A plug 56 closes the opposite end of the cylinder, said plug being held in position in the end of the cylinder by means of the screws 57. Held on the rod 55 is a cylindrical rubber bumper 58 backed by a washer 59 and nuts 60. Extending upwardly from the frame member 30 adjacent the cylinder is an arm 61 which carries a laterally ex-

tending stud 62 on which a roller 63 is mounted. Through the mechanism described, the carriage 15 is, under the action of the chain 42, moved away from the fabric or to the right, as viewed in Figs. 1, 4 and 5. As the carriage, under the push of the chain, is so moved, the stud 21 on the carriage will contact with the projecting end 64 of the plunger rod 55 and force said rod to the right, the disc 65 fixed on said rod with in the cylinder acting to compress the spring 54. This compression of the spring continues until the upwardly projecting end 66 (Fig. 5) of the dog 43 comes into contact with the roller 63. The contact of the roller 63 with the projecting end 66 of the dog 43 will act to disengage the lower end of the dog 43 from the notch 47 in the pawl 23. This will permit the pawl 23 to rise and thus become disengaged from the hook member 41 on the chain. The pawl 23 is caused to rise by reason of the fact that its own weight is not sufficient to overcome the force exerted by the spring 54, tending to drive the carriage 14 to the left of Fig. 6. This force exerted in one direction and the movement of the chain 42 in an opposite direction, act to swing the pawl 23 upwardly about its pivot 24 so that an instant disengagement of the carriage 15 from the chain 42 occurs at the moment that the dog 43 is tripped. As soon as the pawl 23 becomes so disengaged from the hook member 41, the compression of the spring 54 ceases and the spring at once acts on the plunger 55 to cause it to project the carriage 15 rapidly to the left of Fig. 1. At this time, the plate 16 of the carriage is in contact with a head 77 on the end of a pile wire and as the carriage speeds rapidly to the left of Fig. 1, it will vigorously thrust the pile wire in the shed. The pile wire, when not in the fabric, is supported in a channel-shaped guide 67, which is pivoted at one of its ends at 68 in a lug 69 projecting from the frame member 30. Near its other end, the guide 67 is slidingly supported on a lug 70 also projecting laterally from the frame member 30. A link 71 connects the guide 67 to suitable cam mechanism which, at the proper time, moves the guide 67 about its pivot 68 to or from the frame member 31 as required.

The means on the carriage 15 for engaging a pile wire consists of a hook 72 which is pivoted at 73 on the plate portion 16 of the carriage and is spring pressed by means of a spring 74, said spring acting to hold the inner end of the hook 72 against a post 75. The hook 72 is arranged to be brought at the proper time into engagement with an aperture 76 in a plate or head 77 secured at the end of each pile wire 13 for the purpose of drawing the pile wire out of the fabric and moving it into position for insertion into the shed.

Briefly, the operation of the device is as follows: When the carriage is at the extreme left in Fig. 1, the guide 67 is located adjacent to the frame member 30, and the hook 72 on the carriage enters into engagement with the aperture 76 in the pile wire 13a. The drive chain 42 which is an endless chain, driven from a shaft 80 and extending over the sprockets 81, 82, 83 and 84, brings this hook member 41 then into engagement with the end 40 of the pawl 23. At this time, the dog 43 has its lower end engaged with the notch 47 of the pawl and holds the pawl in the position shown in Fig. 3, so that the pawl acts as an abutment for the hook member 41 and as the chain proceeds in the direction of the arrow in Fig. 7, it moves the carriage away from the fabric and toward the right of Figs. 1 and 4. The hook 72,

being engaged with the wire 13a, withdraws said wire out of the fabric and moves it along on the guide 67 which is then in the proper position to receive and support this withdrawn wire. As movement of the carriage to the right of Fig. 1 continues, the stud 21 comes into contact with the end 64 of the plunger 55 and by pressure of the disc 65 on the plunger, the spring 54 is compressed. This action forces the opposite end of the plunger out of the cylinder, as clearly shown in Fig. 1 where the spring has been fully compressed.

Compression of the spring 54 continues until the upper end 66 of the dog 43 strikes the roller 63 which disengages the dog from the pawl 23 and frees the carriage 15 from its engagement with the chain 42. The plunger 55 immediately shoots the carriage to the left of Fig. 1. Just before this propulsion of the carriage to the left begins, the guide 67 is moved to the position shown in Fig. 1 by the pull on the link 71 and by this movement has caused the hook 72 to become disengaged from the aperture 76 in the plate 77 on the wire 13. As clearly seen in Fig. 2, an edge of the plate 16 projects into a slot 90 in the plate 77 so that when the carriage 14 is speedily moved to the left, it propels the wire 13 along on the guide 67 in that direction and into the shed of the fabric. A rubber bumper shown at 86 in Fig. 1 absorbs the shock of the carriage when it reaches the limit of its movement to the left of Fig. 1. The rubber disc 58 on the plunger rod 55 also absorbs the shock of the end of the rod striking against the plug 56. Any suitable buffer means commonly used in looms of this type, may be employed for stopping the pile wires at the opposite side of the shed.

From the foregoing, it will be apparent that the relatively simple structure disclosed will act to speedily and accurately withdraw and insert pile wires without in any way slowing up or impeding the normal, relatively high speed operation of the loom. With the mechanism described, I dispense with a large number of gears, cams and other complex arrangements of parts heretofore used in devices of this character, which not only greatly increased the cost thereof, but tended to impede the high speed operation of the loom.

What I claim is:

1. In a loom, a carriage movable to and from the fabric for withdrawing a pile wire therefrom and then inserting it in the fabric shed, means for engaging the carriage and moving it away from the shed on its withdrawal movement, a plunger, a spring for forcing said plunger in one direction, means on the carriage for compressing the spring while the carriage is moving away from the shed, and means for disengaging the carriage from the carriage-moving means after the spring has been compressed by the carriage.

2. In a loom, a carriage movable to and from the fabric for withdrawing a pile wire therefrom and then inserting it in the shed, a driving chain having means for engaging the carriage and moving it away from the shed on its withdrawal movement, a plunger, a spring for forcing said plunger in one direction, means on the carriage for abutting against the plunger to compress the spring while the carriage is moving away from the shed, and means for disengaging the carriage from the drive chain after the spring has been compressed by the carriage.

3. In a loom, a sliding carriage movable toward the fabric shed for inserting a pile wire

- therein, continuously-moving means for moving said carriage away from the shed, a spring-pressed plunger, means on the carriage for abutting against the plunger and compressing the 5 spring therefor so that the spring is in a compressed condition when the plunger reaches the limit of its movement away from the shed, and means for causing the plunger to thrust the carriage toward the shed.
- 10 4. In a loom, a sliding carriage movable to and from the fabric for first withdrawing a pile wire and then inserting it in the shed, means on the carriage for engaging the wire when the carriage is positioned adjacent to the fabric, a drive chain 15 for moving the carriage away from the fabric, a spring-pressed plunger for forcing the carriage and the pile wire engaged by it toward the fabric, a pawl on the carriage for engaging the drive chain so that said chain moves the carriage away 20 from the fabric, means on the carriage for abutting against the plunger and compressing the spring thereof while the carriage is moved away from the fabric by the drive chain, and means for disengaging the pawl from the drive chain when 25 the carriage reaches the limit of its movement away from the fabric so that the plunger will then act to project the carriage and the wire
- engaged thereby toward the fabric to cause said wire to be inserted in the fabric shed.
5. In a loom, a frame member, a sliding carriage movable on said member to and from the fabric for withdrawing a pile wire from the fabric and then inserting it in the shed, means on the carriage for engaging the wire when the carriage is positioned adjacent to the fabric, a continuously moving drive chain for moving the carriage away from the fabric, said drive chain having a projection for engaging the carriage, a spring-pressed plunger for forcing the carriage and the wire engaged thereby toward the fabric, a pawl on the carriage for engaging the projection on the drive chain so that said chain moves the carriage away from the fabric, means on the carriage for abutting against the plunger and compressing the spring thereof while the carriage is moved away from the fabric by the drive chain, and a fixed projection for causing the pawl to be disengaged from the drive chain when the carriage reaches the limit of its movement away from the fabric so that the plunger will then act to project the carriage and the wire engaged thereby toward the fabric to cause 100 said wire to be inserted in the fabric shed.
